Lever Machine Company, Worcester, Massachusetts

Application May 6, 1968

3 Claims.

This invention relates to impact tools, and

more particularly to a portable impact tool of the reciprocating hammer piston type having novel

reciprocating hammer piston type having novel means for holding the separable parts thereof in assembled relation.

vided separable parts which are maintained in assembled relation by tensioned side rods. Usually in such tools a pair of side rods is employed, arranged in the central longitudinal vertical plane of the tool, and, by such an arrangement, the side rods were found to interfere with compactness and resulted in undesirable projections in or about the supporting handle of the tool which interfered, to some extent, with proper handling of the tool. Furthermore, such a side rod arrangement resulted in a tool which was relatively wide, hindering proper operation of the tool in relatively close quarters. Also, such a side rod arrangement prevented the application of equally distributed clamping pressures to the tool parts.

In the present invention a novel means is provided for holding the separable tool parts in assembled relation which to a large extent overcomes the disadvantages of the previous known devices, in that the tool is rendered extremely compact in width and undesirable projections in and about the tool supporting handle are completely avoided. Also by the novel holding means provided, the separable parts of the tool are held in assembled relation in a better manner, in that greater ruggedness is attained as well as extreme lateral compactness. By the novel holding means provided, the tool supporting handle and its mounting are enabled to be "streamlined" to a large degree, thereby making handling of the tool easier.

It is accordingly an object of the present invention to provide novel means for holding the separable parts of a portable impact tool in assembled relation which overcomes, to a large extent, the disadvantages of previously known devices. Another object is to provide a novel tension-bolt arrangement for holding the separable tool parts assembled, which lends itself to greater compactness and ruggedness. A further object is to provide a novel tension-bolt arrangement, whereby all undesirable projections in and about the mounting means for the tool supporting handle are avoided. A still further object is to provide a novel U-bolt structure for holding the separable parts of an impact tool in assembled relation. How these and other objects are accomplished, and the advantageous features of

7,977 *Patent Office*

IT TOOL *IT* is the name of the
entity, N. H., assignor to Sul-
Company, a corporation of

42, Serial No. 442,001

the invention, will be best understood from the following detailed description wherein a preferred and illustrative embodiment is set forth, reference for the purpose being had to the accompanying drawing, in which:

Fig. 1 is a front elevational view of an impact tool constructed in accordance with an illustrative embodiment of the invention.

Fig. 3 is a view in longitudinal vertical section,

with parts in elevation, taken substantially on line 3-3 of Fig. 2.

Fig. 5 is a cross sectional view taken substantially on line 5—5 of Fig. 1.

In this illustrative embodiment of the invention, the improved means for holding the separ-

0 able tool parts in assembled relation is shown embodied in a portable impact tool of the type known as a hand-held "buster," although it will be evident that the invention may be incorporated in impact tools of other types in an equally ad-
5 vantageous manner.

The portable "buster" disclosed comprises a motor cylinder 1 having a bore 2 provided with front and rear heads 3 and 4. The cylinder bore contains a reciprocatory hammer piston 5 for delivering impact blows to a tappet 6 reciprocably mounted in the front head, and the piston blows are transmitted by this tappet to the shank 7 of a suitable working implement such as a demolition pick or clay digger. The working implement has its shank mounted in a chuck 8 supported within a front chuck housing 9 arranged at the front end of the cylinder. A valve block 10 is arranged at the rear end of the motor cylinder and contains a conventional distributing valve mechanism 11 for distributing motive fluid to the motor cylinder to effect reciprocation of the hammer piston. Arranged rearwardly of the valve block is a supporting head 12 for a handle 13 by which the tool may be manually supported with respect to the work. This handle has oppositely extending grasping portions 14, 14 lying in a central longitudinal vertical plane of the tool. Suitably attached to the valve block is a hose connection 15 through which motive fluid may flow to the valve mechanism 11, and this connection lies beneath one of the grasping portions of the tool supporting handle. Such a tool construction is generally well known to those skilled in the art.

Now referring to the novel means for holding

the separable parts 1, 3, 4, 9, 10 and 12 of the tool in assembled relation, it will be noted that the rear supporting head 12 for the handle has lateral lugs 16, 16, relatively smooth in exterior contour and projecting from the supporting head at right angles with respect to the handle grasping portions 14, 14 at the opposite sides of the tool, and these lugs have arcuate grooves 17 near the opposite sides of the tool. A pair of U-bolts 18, 18 extend longitudinally in parallelism at the opposite sides of the tool and have their rearward curved U-portions 19 received in the lug grooves 17. The legs 20 of the U-bolts extend longitudinally along the sides of the tool cylinder and pass through perforations 21 in lugs 22 integral with the rearward part of the front chuck housing 9. Threaded at 23 on the forward extremities of the U-bolt legs are tightening nuts 24, and preferably interposed between these nuts and the chuck housing lugs 22 and surrounding the U-bolt legs are coiled tensioning springs 25. The nuts may be adjusted to place the springs under compression, thereby to maintain the U-bolts under tension, in an obvious manner. A downwardly sloping, piston-controlled exhaust passage 26 opens through a side of the cylinder between the U-bolts 18, 18.

By such an improved arrangement, the handle may be constructed to lie midway between the U-bolts, and the grooved lugs on the handle supporting head project laterally at the sides of the handle portions and due to this novel construction, it has been possible to "streamline" the handle mounting so that undesirable projections are avoided. Further by the novel arrangement of the U-bolts, it has been possible to maintain the width of the tool at a minimum and due to the symmetrical design, the tool is rendered extremely well balanced, so that it may be easily handled. Also by the provision of the novel U-bolt arrangement, substantially equal clamping pressures are applied to the tool parts, resulting in a better holding action. And with the exhaust passage 26 and the supply connection 15 bisected by a common plane including the axis of the cylinder and the axis of the manual grasping handle, a very convenient arrangement is produced. It will furthermore be noted, by reason of the relatively large flat areas on the sides of the cylinder 1, there are provided surfaces which the leg, and particularly the knee, of the operator can engage in handling the tool to great advantage. Other advantages of the invention will be clearly apparent to those skilled in the art.

While there is in this application specifically described one embodiment which the invention may assume in practice, it will be understood that this embodiment of the same is shown for purposes of illustration and that the invention may be modified and further embodied in various other forms without departing from its spirit or the scope of the appended claims.

What I claim as new and desire to secure by Letters Patent is:

1. In a portable impact tool, a tool body including a plurality of cooperating parts including a rear handle part, an intermediate motor cylinder part and a front chuck part, said chuck part having perforated lugs, and said rear handle part having oppositely extending grasping portions lying in a series of parallel longitudinal planes one of which includes the longitudinal axis of the tool, said rear handle part also having lateral lugs located at the opposite sides of said

longitudinal planes in which said grasping portions lie and having arcuate grooves, and U-bolts extending longitudinally in parallelism at the opposite sides of the tool body entirely within the longitudinal limits of the tool body, said U-bolts having their curved rearward U-portions received in said arcuate lug grooves in close proximity to the sides of the tool body, and having their parallel leg portions extending longitudinally along the sides of the tool body through the lug perforations of the front chuck part, the sides of the motor cylinder part projecting between said leg portions and at least the one of said sides nearer the operator as he handles the tool providing a relatively smooth surface of substantial area between said leg portions for engagement by the leg of the operator in manipulating the tool, and said U-bolts lying in longitudinal planes parallel to any being spaced equi-distantly from the closest one of said longitudinal planes in which said grasping portions lie, said leg portions having threaded forward free extremities and tightening nuts threaded on said extremities and adjustable to tension said U-bolts to clamp the tool body parts together.

2. In a portable impact tool, a tool body including a plurality of cooperating parts including a rear handle part, an intermediate motor cylinder part and a front chuck part, said chuck part having perforated lugs and said rear handle part having oppositely extending grasping portions lying in a series of parallel longitudinal planes one of which includes the longitudinal axis of the tool, said rear handle part also having lateral lugs located at the opposite sides of said longitudinal planes in which said grasping portions lie and having arcuate grooves, and U-bolts extending longitudinally in parallelism at the opposite sides of the tool body entirely within the longitudinal limits of the tool body, said U-bolts having their curved rearward U-portions received in said arcuate lug grooves in close proximity to the sides of the tool body with the inner portions of said grasping portions lying between said rearward curved U-bolt portions with said curved portions disposed in close proximity to said grasping portions, and having their parallel leg portions extending longitudinally along the sides of the tool body through the lug perforations of the front chuck part, the sides of the motor cylinder part projecting between said leg portions and the side nearer the operator when the tool is in use providing a relatively smooth surface for contact with the leg of the operator in the handling of the tool, and said U-bolts lying in longitudinal planes parallel to and being spaced equi-distantly from the median one of said parallel longitudinal planes in which said grasping portions lie, said leg portions having threaded forward free extremities and tightening nuts threaded on said extremities and adjustable to tension said U-bolts to clamp the tool body parts together.

3. In a portable impact tool, a tool body including a plurality of cooperating parts including a rear handle part, an intermediate motor cylinder part and a front chuck part, said chuck part having perforated lugs with the perforations thereof spaced equi-distantly from each other at equal distances with respect to the longitudinal axis of the tool and said rear handle part having oppositely extending grasping portions lying in a series of parallel longitudinal planes one of which includes the longitudinal axis of the tool, said rear handle part also hav-

ing lateral lugs located at the opposite sides of said longitudinal planes in which said grasping portions lie and having arcuate grooves, and U-bolts extending longitudinally in parallelism at the opposite sides of the tool body entirely within the longitudinal limits of the tool body, said U-bolts having their curved rearward U-portions received in said arcuate lug grooves in close proximity to the sides of the tool body, and having their parallel leg portions extending longitudinally along the sides of the tool body through the lug perforations of the front chuck part, the sides of the motor cylinder part projecting between said leg portions and providing at least at the side of said tool which is nearer the op-

erator when said tool is in use a smooth surface of substantial area for engagement by the knee of the operator in the handling of the tool, and said U-bolt lying in longitudinal planes parallel to and being spaced equi-distantly from that one of said longitudinal planes in which said grasping portions lie which includes the longitudinal axis of the tool, said leg portions having threaded forward free extremities and tightening nuts 10 threaded on said extremities and adjustable to tension said U-bolts to clamp the tool body parts together.

15 JOHN C. CURTIS.

CERTIFICATE OF CORRECTION.

Patent No. 2,385,797.

October 2, 1945.

JOHN C. CURTIS.

It is hereby certified that error appears in the printed specification of the above numbered patent requiring correction as follows: Page 2, second column, line 19, claim 1, for the words "to any" read --to and--; line 71, claim 3, after "tool" insert a comma; page 3, second column, line 4, same claim, for "U-bolt" read --U-bolts--; and that the said Letters Patent should be read with this correction therein that the same may conform to the record of the case in the Patent Office.

Signed and sealed this 1st day of January, A. D. 1946.
